(57) **CLAIM**

The ornamental design for a docking station, as shown and described.

DESCRIPTION

An example of a representative electronic device is shown and described, for example, in U.S. Design Pat. No. D538, 820 and entitled “Media Device,” which is hereby incorporated by reference.

FIG. 1 is a top front perspective view of a docking station showing our new design;

FIG. 2 is a top rear perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof;

FIG. 8 is a right side view thereof;

FIG. 9 is a front view of a representative electronic device being inserted into the docking station;

FIG. 10 is a front view of the docking station with the representative electronic device inserted therein; and,

FIG. 11 is a side view of the docking station with the representative electronic device inserted therein.

The broken lines in the Figures show portions of the docking station that form no part of the claimed design. The broken lines in the Figures showing the representative electronic device show environmental structure only and form no part of the claimed design.

The shade lines in the Figures show contour and not surface ornamentation.
